DESIGN FOR A FISHING REEL

Hyla F. Maynes, North Tonawanda, N. Y.

Application November 22, 1935, Serial No. 59,707

Term of patent 14 years

To all whom it may concern:

Be it known that I, Hyla F. Maynes, a citizen of the United States, residing at North Tonawanda, in the county of Niagara and State of New York, have invented a new, original, and ornamental Design for a Fishing Reel, of which the following is a specification, reference being had to the accompanying drawing, forming a part thereof.

In the drawing:

Fig. 1 is an end elevational view of the fishing reel;

Fig. 2 is a plan view of the fishing reel; and

Fig. 3 is a front elevational view of the reel showing my new design.

I claim:

The ornamental design for a fishing reel, as shown.

HYLA F. MAYNES.
